United States Patent Office

Des. 207,755
Patented May 23, 1967

207,755

DOOR CHIME OR SIMILAR ARTICLE

Norman William Stevenson, Macclesfield, England, assignor to V. & E. Friedland Limited, Macclesfield, England, a British company

Filed Jan. 15, 1965, Ser. No. 83,466

Claims priority, application Great Britain July 29, 1964

Term of patent 14 years

(Cl. D72—1)

FIG. 1.

FIG. 2.

FIG. 3.

FIG. 4.

FIGURE 1 is a front elevational view of a door chime or similar article showing my new design,

FIGURE 2 is a rear elevational view of the chime of FIGURE 1,

FIGURE 3 is a plan view of the chime of FIGURE 1, and

FIGURE 4 is a side elevational view of the chime of FIGURE 1.

I claim:

The ornamental design for a door chime or similar article, substantially as shown.
